Inventor,

Walter Shriver

United States Patent Office.

WALTER SHRIVER, OF NEW YORK, N. Y.

Letters Patent No. 65,290, dated May 28, 1867.

RESERVOIR DAMPING-BRUSH.

The Schedule referred to in these Letters Patent and making part of the same.

TO WHOM IT MAY CONCERN:

Be it known that I, WALTER SHRIVER, of the city of New York, county of New York, and State of New York, have invented a new and improved Reservoir Damping-Brush for wetting paper in the operation of copying letters; and I do hereby declare that the following is a full and exact description thereof, reference being had to the accompanying drawings, and to the letters of reference marked thereon, in which—

Figure 1 is a vertical longitudinal section; and

Figure 2 a vertical cross-section of the same.

The nature of my invention is to provide the ordinary brush for damping paper with a suitable reservoir or fountain within the handle to contain a supply of water, thus doing away with the inconvenience of a separate vessel for containing the water; liability to evaporation, deterioration from dust, &c.

To enable others skilled in the art to make and use my invention, I will proceed to describe its construction and operation.

A represents a suitable flat brush, composed of the usual material, secured to the clamp-head C, which is kept in its position by the supports g g. The handle B is made hollow, of sheet metal, and of sufficient capacity to contain a suitable supply of water. It is of a flat or oval form, in cross-section, with an enlarged portion at b b, as seen in the drawings, but having the lips or lower edges contracted at h h, so as to form a narrow slit sufficiently close to give proper compression to the hair of the brush, as hereafter described. The handle is made otherwise water-tight, being entirely closed at the upper end, except a small opening at E, provided with an inner opening valve, F, which has a stem projecting through the opening E and terminating in a button, e', by which it may be operated, at such times as may be necessary, for the admission of air, by simple pressure from without. This valve is retained in a normally closed position by the action of the spring f. An opening is also provided at D for the purpose of introducing the water into the reservoir, which opening D is provided with a screw-cap, or other suitable fastening, to render it water-tight.

The hair of the brush A having been properly secured by the clamp-head C, is inserted within the handle B in such a manner that the lips h h shall bear upon and compress the hair at a suitable point between the outer ends of the hair and the clamp-head C, and with just sufficient force to permit the water to flow out by capillary attraction when the brush is being used for damping paper, and the aperture at E is opened to admit the necessary amount of air. The hair of the brush is held firmly in position by the supports g g, which are secured at one end to the clamp-head, and at the other to the inner sides of the handle, at or near the angle of enlargement, as seen in the figures.

A ring, G, for hanging up the brush when not in use, is also provided; its position with reference to the centre of gravity of the handle being such that the brush will always hang with the reservoir downward, and thus prevent any leaking and dripping from the brush when hung up.

Having now described my invention, what I claim as new, and desire to secure by Letters Patent, is—

As a new article of manufacture, a reservoir damping-brush for wetting paper for copying letters, arranged and constructed substantially as and for the purpose described.

WALTER SHRIVER.
